UNITED STATES PATENT OFFICE.

THOMAS WARNOCK BIGONEY, OF NEW YORK, N. Y.

DISPENSING-TOP FOR CONTAINERS.

1,249,289.

Patented Dec. 4, 1917.

Application filed April 4, 1917. Serial No. 159,677.

To all whom it may concern:

Be it known that I, THOMAS WARNOCK BIGONEY, a citizen of the United States, and a resident of the city of New York, borough 5 of Manhattan, in the county and State of New York, have invented certain new and useful Improvements in Dispensing-Tops for Containers, of which the following is a specification.

10 This invention relates to certain improvements in dispensing tops for containers and more particularly to that general type shown in my prior Patent No. 1,199,522, issued September 26, 1916.

15 In the construction there shown, I provide a slide having an aperture which may be moved into and out of registry with the dispensing aperture of the container and which slide has formed as a part thereof a spring, 20 tongue, or extension, which engages with a part of the container, to normally hold the slide in a predetermined position with the apertures out of registry.

25 One object of my present invention is to provide a simple and efficient means for locking the slide or cut off in either open or closed position, and a further object is to reduce to a minimum the liability of the material sifting out from the container when 30 the slide is in closed position.

35 My invention may be applied to containers for various different kinds of material such, for instance, as toilet preparations, condiments, or other powders or pastes and 40 may be embodied in various different forms within the scope of my invention.

The specific form illustrated in the accompanying drawings is designed for talcum powder, although I wish it particularly 45 understood that I am not to be limited either to this material or to the details of such specific form. In these drawings, to which reference is to be had and in which similar reference characters indicate corresponding parts in the several views,

Figure 1 is a perspective view of a container having a top embodying my invention;

Fig. 2 is a perspective view of the top on a 50 very much larger scale;

Fig. 3 is a horizontal section in a plane just above the slide;

Figs. 4 and 5 are transverse sections on the lines 4-4 and 5-5, respectively, of Fig. 3; and

Fig. 6 is a perspective view of a modified form.

I have illustrated my invention as applied to a container 10 of a size and form commonly employed for talcum powder and terminating at its upper end in a neck 11. The neck is illustrated as having a peripheral wall 12 and a top wall 13 integral therewith and secured to the body of the container in any suitable manner. The top wall 13 has a central portion 14 countersunk to a slightly lower level than the opposed side portions 15. The extent to which this is countersunk may be comparatively slight and preferably is only of an extent approximately equal to the thickness of the slide hereinafter referred to. The countersunk portion may extend diametrically across the top wall 13 entirely from one side to the other, or may terminate short of the peripheral wall at one or both ends so that one side portion 15 may be connected to the other by a peripheral flange 16 as illustrated in Fig. 6. The edges 17 of the side portions are preferably substantially straight and parallel.

Fitting over these parts is a cap 18 which also has a peripheral wall 19 and a top wall 20. The peripheral wall 19 may be secured to the peripheral wall 12 in any suitable manner, forming no portion of my present invention. As shown, it is spun, bent or crimped inwardly at its lower edge so as to permanently retain it in position. It might be soldered if desired or held merely by 90 wedging or friction action.

The top wall 20 lies directly upon the side portions 15 of the top wall 13 and is spaced from the countersunk portion 14 to an extent substantially equal to the thickness of the slide. I have shown the wall 13 as having the countersunk portion for the slide and have shown the top wall 20 substantially flat save for a peripheral head or flange, but it will of course be evident that it is immaterial which of the top walls is countersunk and provides the guiding edges for the slide, as the top wall 13 might be flat and the top wall 20 countersunk upwardly or the space

- for the slide might be formed by displacing portions of both of the top walls in opposite directions and to only one-half the thickness of the slide.
- 5 Between the two top walls and within the countersunk portion or guideway, is a slide 21. This is formed of a thin piece of sheet metal and preferably has opposite, substantially parallel, side edges. The width 10 of the slide is preferably slightly less than the distance between the edges 17 so that the slide may have a comparatively slight lateral turning or rotative movement as hereinafter described. The slide has a tongue 22 at 15 one end thereof and preferably integral therewith and this tongue extends through a slot in the peripheral wall 19. The outer end of the tongue constitutes not only a handle for the operating of the slide, but also 20 constitutes a spring for normally holding the slide in a predetermined position. The tongue is bent downwardly to engage with some portion of the wall of the container and is of spring or resilient material so that 25 it operates substantially as disclosed in my prior patent above referred to.
- As an important feature of my invention, I provide means whereby the slide may be locked in either of its two limiting positions.
- 30 As illustrated, this locking means includes two notches 23 and 24 in the side edge of the tongue and so positioned that the tongue may be moved laterally to bring the peripheral wall of the cap at the end of the slot 35 of the latter into either of these two notches when the tongue and slide are moved endwise to the proper registering position. The slot is of a length substantially equal to the width of the portion of the tongue passing 40 therethrough so that the tongue may be freely pressed inwardly and returned by the spring action, but with the tongue in its outer position, as shown in dotted lines in Fig. 3, the slight free play between the 45 edges of the slide and the edges 17 permits the tongue to be moved laterally and locked. When the slide is forced inwardly to the limiting extent, the other notch will come adjacent to the end of the slot and the 50 tongue may be moved laterally to lock the slide in its inner position, as indicated in dotted lines in Fig. 3.
- As the spring tongue tends to hold the slide in one of the two limiting positions, 55 it is of course evident that the notch 24 might be omitted and in fact in most constructions it is unnecessary.
- The top walls 13 and 20 and the slot 21 have apertures which permit the dispensing 60 of the contents when the slide is in one position and prevent it when in the other position. The character, size, number and location of these apertures may vary with the character of the contents to be dispensed.
- 65 As shown, the two top walls have apertures
- which at all times register and the slide has a corresponding set of apertures which register only when the slide is moved inwardly to the limiting position. For coarser material, the number of apertures would be correspondingly larger and might be fewer in number. For a plastic material, such as shaving cream, tooth paste, or the like, a single aperture might be provided in each of the two top walls and in the slide. It 70 will of course be evident that the cut-off action of the slide is effected by the bringing of its aperture or apertures into or out of registry with those of one of the top walls and the fact that both top walls have 75 the same set of apertures merely insures the more effective sealing of the container. If such effective sealing is not necessary by reason of the character of the material being dispensed, the center portion of either 80 of the two top walls may be cut away to form a single large aperture and the cut-off action secured by the relative movement of the slide and the other top wall. I have 85 shown such a construction in Fig. 6.
- 90 It will be noted that the locking action is effected by a slight rotary or lateral movement of the slide in respect to one of the top or peripheral walls. It will be evident that the slide might be of such width that no lateral or rotary movement between the edges 17, 17, would be possible and that the cap itself might be rotated to a slight extent to bring the wall at the end of the slot into the notch in the tongue when the tongue and slide are in proper registering position. The tongue and slide being held against rotary movement in respect to the inner top wall would constitute a stop for limiting the 100 rotary locking movement of the cap.
- 105 Having thus described my invention, what I claim as new and desire to secure by Letters Patent is:
1. A receptacle having two superposed top walls, a slide movable endwise to a predetermined extent, said walls and slide having dispensing openings brought into and out of registry by said movement, a slide operating member rigid therewith, and means for locking said slide against endwise movement by a lateral movement of said member in the plane of said slide. 110
2. A receptacle having a wall, a slide adjacent thereto and movable endwise in respect thereto, said slide and wall having apertures which may be brought into and out of registry by said endwise movement and a slide operating member rigid therewith and provided with a locking notch in one edge thereof whereby upon a relative 120 lateral movement of said slide and wall, said slide may be locked against endwise movement.
3. A receptacle including a top wall, a peripheral wall, and a slide movable in re- 125
- 130

spect thereto and having a tongue integral therewith projecting through said peripheral wall, said tongue being movable endwise to bring said slide into and out of operative position and said tongue and said peripheral wall being relatively movable laterally to lock said slide against endwise movement.

4. A receptacle including a top wall and a peripheral wall, and a slide having a body portion coating with said top wall to control the dispensing of the contents of the receptacle, and a tongue projecting through said peripheral wall for operating said slide, said tongue having a resilient portion for engagement with a portion of the container and normally tending to move said slide endwise to one limiting position and the edge of said tongue having a recess adapted to interlock with said peripheral wall to prevent said endwise movement.

5. A receptacle having an apertured top wall provided with a central countersunk portion presenting parallel side edges, a cap having an apertured top wall and a peripheral wall, and a slide having an apertured body portion movable within said countersunk portion between said top walls and guided by said parallel edges, and said slide also having a tongue projecting through said peripheral wall, the terminal portion of said tongue being resilient and engaging with the wall of the container to normally move said slide endwise in one direction to non-apertured registering position, and the edge of said tongue having a recess adapted to coat with said peripheral wall upon a slight relative lateral move-

ment of said tongue and peripheral wall to lock said slide in a predetermined position.

6. A receptacle having an apertured top wall provided with a central countersunk portion presenting parallel side edges, a cap having an apertured top wall and a peripheral wall, and a slide having an apertured body portion movable within said countersunk portion between said top walls and guided by said parallel edges, and said slide also having a tongue projecting through said peripheral wall, the terminal portion of said tongue being resilient and engaging with the wall of the container to normally move said slide endwise in one direction to non-apertured registering position.

7. A receptacle having an apertured top wall provided with a central countersunk portion presenting parallel side edges, a cap having an apertured top wall and a peripheral wall, a slide having an apertured body portion movable within said countersunk portion between said top walls and guided by said parallel edges, and said slide also having a tongue projecting through said peripheral wall, the terminal portion of said tongue being resilient and engaging with the wall of the container to normally move said slide endwise in one direction to non-apertured registering position, and means for locking said slide against endwise movement.

Signed at New York, in the county of New York, and State of New York, this 29th day of March, A. D. 1917.

THOMAS WARNOCK BIGONEY.
